WRAPPING MACHINE

Alfred German Rose, Gainsborough, England, assignor to Rose Brothers (Gainsborough) Limited, Gainsborough, England, a British Company

Application July 7, 1934, Serial No. 734,135
In Great Britain May 22, 1933

16 Claims. (Cl. 93—7)

This invention is for improvements in or relating to wrapping or packeting machines of the kind in which an article to be wrapped, such as a block or charge of tobacco, is pressed into a mould lined with a sheet of wrapping material having free ends or flaps projecting from the mould, which flaps are folded and laid over the exposed surfaces of the article, to produce a wrapped package. A machine of this kind is fully described in United States patent specification No. 586,076.

In machines of this kind, as hitherto proposed, the flaps of the wrapping material have each been folded and laid over the article by a layer-member which engages the outer surface of the upstanding flap and is then moved in the appropriate direction with the result that the flap rotates as a whole about one edge of the article and is constrained into the desired position by further movement of the layer-member. Machines of the kind described have also incorporated means, termed a flap-lifting device, for moving a flap into, or supporting it in, a position in which the layer-member can engage it.

Whereas such machines are satisfactory where comparatively stiff wrapping material is used, it is found that where the wrapping material employed is very thin or fragile, such as thin metal foil or thin sheets of the material sold under the registered trade-mark "Cellophane", there is a tendency for the flaps to collapse, buckle, distort or tear during the folding or laying operations or during the operation of the flap-lifting device, and it is the principal object of the present invention so to modify wrapping or packeting machines of the kind described as to enable very thin or fragile wrapping material to be used.

According to the present invention, in or for a wrapping or packeting machine of the kind described, there is provided, in combination, a controlling device to engage the flap on the side opposite the layer-member and means to move the controlling device in company with the layer-member during the laying operation.

According to another feature of the invention, there is provided the combination with the layer-member, of a controlling device to engage the flap on the opposite side from the layer-member and thereby to support the flap during the laying operation, and means to move the controlling device in advance of the layer-member and in the same sense; preferably, the controlling device engages the flap at a point further from the article to be wrapped than the point of engage-

ment of the layer-member with the wrapper; the purpose of this arrangement is to ensure that, during the laying operation, the flap shall be curved backwardly towards the layer-member, whereby the possibility of distortion or buckling in the flap is eliminated as hereinafter more fully explained.

According to another feature of the present invention the said controlling means also engages the flap prior to the folding or laying operation so as to co-operate with the flap-lifting device in positioning the flap.

While the invention may be applied to any machine of the kind above described, it is particularly applicable to a machine of that known form in which the moulds are arranged around the periphery of a mould-wheel or drum and in which each sheet of wrapping material is so placed in the appropriate mould that one flap is considerably longer than the other; when the longer flap is folded and laid over the exposed surface of the article to be wrapped, its end overhangs the other side of the article and is subsequently folded down on to the side of the article in a manner hereinafter more particularly explained.

A specific embodiment of the present invention will now be described by way of example with reference to the accompanying drawings, of which—

Figures 1 and 2 are views of parts of the mould-wheel, of a wrapping machine, according to the invention, and the associated parts.

Figures 3, 4, 5, 6 and 7 are detailed views, to an enlarged scale, of the mould and layer-member, showing the controlling device, according to the invention.

Figure 8 is a plan view of the controlling device and corresponds to Figure 5, and

Figure 9 is a view showing the arrangement for operating the layer member and controlling device.

Referring first to Figures 1 and 2, a mould-wheel 10 carries moulds 11 around its periphery. For example, in the machine illustrated, there would be twelve moulds 11 on the wheel 10. Each of the moulds 11 comprises a fixed side and bottom and a movable side or jaw 12 which is rotatable about a pivot 13 in known manner.

Situated above the mould-wheel is a chute 14 for tobacco or other material which is to be wrapped up in the form of packets and a presser 15 operates to press the charge of tobacco entering the mould into a compact block 39 (see Figure 2).

- Sheets of wrapping material are fed into the operating position by means of an endless conveyor-chain 16 having hooks 17 each of which engages the edge of a sheet of the material and feeds it along. When a sheet of wrapping material reaches a point near to the mould-wheel 10, a trigger 18 is operated by means of links 19 and 20 to throw the sheet on to a platform 21 which has stops 22 to limit the movement of the sheet.
- 10 The platform 21 is in the form of two rails, one each side of the mould-wheel, and the stops 22 are adjustable on these rails by means of bolts 23. When the sheet of wrapping material is in position on the platform 21, the platform is rotated downwardly by means of the arm 24 and at the same time, a plunger 25 is moved by an arm 26 into the position shown in Figure 2. It will be seen that the wrapper is thus pressed into the mould with two projecting flaps 27 and 28 standing clear. The rear flap 27 is considerably longer than the front flap 28. The plunger has a ledge 29 formed on its front edge so that the forward flap 28 is bent over as shown in Figure 2.
- 25 The mould-wheel is now rotated to bring the mould having the sheet of wrapping paper within it beneath the chute 14 through which a charge of tobacco or other material falls into the lined mould. During the rotation of the mould-wheel the edges of the sheet of wrapping material which project laterally from the mould-wheel are held in position by means of gripping devices which are not illustrated in the drawings nor described in the present specification but are well known in machines of this kind. The presser 15 compresses the charge of tobacco into a compact block and the mould-wheel moves on to the next position.
- When the mould 11 reaches the position shown at 30 in Figure 2, a flap-lifter, which will be described with reference to Figures 3 to 8, lifts the longer flap 27 into the position shown at the right-hand side of Figure 1 in readiness for engagement by the layer-member 31.
- 40 Referring now to Figure 3, the flap-lifter is shown at 32. This device is itself known in wrapping machines of the kind described and is disclosed, for example, in British patent specification No. 270,866. The layer-member 31 is carried on an arm 33 which is rotatable about a spindle or axle 34. The controlling device according to the invention takes the form of a rod 35 which is carried on two arms 36 which are formed integrally or otherwise rigidly connected 45 with the arm 33 of the layer-member 31. The arrangement of these parts can be seen from Figure 8.
- When the flap-lifter 32 engages the flap 27, the layer-member 31 is in its uppermost position 60 as shown in Figure 3 and the controlling device 35 is therefore also in its uppermost position and a row of pegs 37 carried by the rod 35 projects and engages the rear surface of the flap 27 and thus co-operates with the flap-lifter 32 to hold the flap 27 in position in readiness for engagement of the flap by the layer-member 31.
- 65 As has been explained above, the present invention is particularly applicable to machines of the kind described for use with wrapping material which is very thin or flimsy and it is found that the row of pegs 37 offers sufficient support to the rear surface of the flap 27 to prevent it from collapsing or buckling when held in the position shown in Figure 3 by the flap-lifter 32.
- 70 The arms 33 and 36 are now rotated in the di-

rection of the arrow shown in Figure 3 so that the controlling device 35 moves away from the flap 27 and the layer-member 31 engages with the flap. As soon as the layer-member engages the flap, the flap 27 falls over, rotating about the nearest edge of the block of tobacco 39, but it is prevented from collapsing into a crumpled or irregular shape by the pegs 38 which are also carried on the rod 35.

The flap therefore takes up the position shown in Figure 4 and it will be seen that the effect of the pegs 38 is to cause the flap to assume a backwardly-bent configuration towards the layer-member 31. As the layer-member moves along the flap, by reason of the configuration of the flap shown in Figure 4, the flap is subjected to gentle tension and any distortion or crumpling is smoothed out by the passage of the layer-member.

As explained above, the ledge 29 of the plunger 25 ensures that the shorter flap 28 shall be bent outwardly, but with very thin or very flexible packing material there is a possibility of the shorter flap 28 springing back into the path of the longer flap 27. For this reason, the controlling device is so arranged that the rod 35, as shown in Figure 4, strikes against the shorter flap 28 and pushes it aside out of the path of the longer flap 27. It is thus impossible for the shorter flap 28 to become entrapped under the longer flap 27.

When the layer-member and the controlling device reach the position shown in Figure 5, the end of the longer flap 27 falls from the peg 38 on to the lower peg 37. The extent to which the flap 27 is bent backwardly thus decreases towards the end of the laying operation.

The final stage in the laying operation is shown in Figure 6 in which the layer-member 31 has reached the limit of its travel, and is pressed down flat on the block of tobacco 39. At this stage of the operation, the movable jaw 12 of the mould is rotated outwardly about its pivot 13 so as to uncover the forward edge of the block of tobacco and so as to allow the shorter flap 28 to fall outwardly into the position shown.

A finger 40 rotatable about a pivot 41 on the main frame of the machine, and controlled by a cam in known manner, descends and folds the overhanging edge of the longer flap 27 down the side of the block of tobacco. The jaw 12 then moves back into its original position as shown in Figure 7 and, at the same time, the finger 40 is retracted.

It remains to fold down the shorter flap 28 on to the top of the tobacco block 37 and over the longer flap 27. The folding of the shorter flap 28 is effected by a pivoted bar of known construction (not shown) but the flap is constrained in the general direction desired by the engagement with it of the pegs 37 on the rod 35 which engagement occurs either when the arms 33 and 36 are returned to their initial position as shown in Figure 3 or else when the mould-wheel is rotated through another step.

As shown in Figure 9, the layer member 31, and the controlling device 35, which are carried by the arms 33 and 36 respectively, on the shaft 34, are operated by a lever 50 on the shaft 34 engaging a rod 51, the other end of which is pivoted to a lever 52 rotatable about an axle 53 fixed to a part 54 of the frame of the machine.

The lever 52 carries a roller 55 which engages with the edge of a cam 56 which is rotated by a shaft 57 which also carries a sprocket (not shown)

for the chain 16. The chain thus drives the cam.

The roller 55 is held in engagement with the cam 56 by the action of a tension spring 58 which acts between the lever 58 and fixed point 59 on the frame 54. It will be seen that as the cam 56 rotates the lever 52 will be rocked by the action of the spring 58, whereby the controlling device 35 and the layer member 31 will be operated in the manner described with reference to Figures 3 to 8.

It will be understood that the three stages above described, namely, inserting the paper, inserting the tobacco, and folding the two flaps, all take place simultaneously on three different moulds.

11. As each mould moves from left to right as shown in Figure 1, it first receives the paper, then the tobacco, and then the flaps are folded as above described. The mould-wheel is rotated intermittently by mechanism of known construction.

12. The form of wrapper employed, namely, that in which one of the flaps is considerably longer than the other, is preferable since it results in a superior form of package, but in the invention can also be applied to a form of package in which the flap 27 does not overhang the surface of the tobacco block 31. In this modification, the pivoted arrangement of the jaw 12 might be dispensed with and the rotating finger 40 (Figure 6) would be unnecessary.

13. The form of controlling device 35, 37, 38, described and illustrated, is not the only form which might be used. For example, instead of separate pegs 37 and 38 each row might be replaced by a bar and the two bars might be formed integrally with one another so as to make an L-shaped bar supported at its angle on the rod 35. Alternatively, in some forms of machine of the kind described, it might be possible to dispense with one row of pegs 37 or 38, or with the corresponding bar, and to use a single projection or sets of projections.

I claim:

1. A machine of the class described comprising a layer-member, a controlling device to engage a flap on the side opposite the layer-member during the major portion of the laying operation, and means to move the controlling device in company with the layer-member and in the same direction during the laying operation.

2. In a machine of the class described, the combination with a layer-member of a controlling device to engage a flap on the side opposite to the layer-member, and thereby to support the flap during the major portion of the laying operation, and means to move the controlling device in advance of the layer-member and in the same sense.

3. A machine of the class described comprising, in combination, a layer-member, a controlling device to engage a flap on the side opposite the layer-member, and thereby to support the flap during the major portion of the laying operation, and means to move the controlling device in advance of the layer-member and in the same sense and at the same speed.

4. A machine of the class described comprising a layer-member, a controlling device to engage a flap on the side opposite the layer-member and also to engage the flap prior to the folding or laying operation so as to co-operate with a flap-lifting device in positioning the flap, and means to simultaneously move in the same direction the controlling device in company with the layer-member during the laying operation.

5. A machine of the class described comprising

a layer-member, a controlling device to engage a flap on the side opposite the layer-member during the laying operation, and means to simultaneously move the controlling device in company with the layer-member and in the same direction during the laying or folding operation, the controlling device being arranged to also engage, during its travel, another flap of the wrapping sheet so as to move it out of the path of the first said flap.

6. A machine of the class described wherein a wrapper is so disposed in a mould that one flap is longer than the other flap and is folded on to the front edge of the article by means of an auxiliary finger, comprising, in combination, a layer-member, a controlling device to engage the longer flap on the side opposite the layer-member, means to move the controlling device in advance of the layer-member and in the same sense and means to move the shorter flap out of the path of the longer flap during the laying operation.

7. In a wrapping machine, the combination with a layer member, of means for engaging the flap to be laid on the side opposite that engaged by the layer member throughout the major portion of the laying operation and movable progressively from a point intermediate the flap toward the free edge of the flap, said layer member and said means being arranged for simultaneous movement in the same direction.

8. In a wrapping machine, the combination with a layer member of a controlling device to engage and support a flap on the side opposite the layer member, said controlling device having a plurality of projections thereon for successively engaging the wrapper on the side opposite the layer member during the laying operation.

9. In a wrapping machine, the combination with a layer member of a controlling device to engage and support a flap on the side opposite the layer member, said controlling device having a plurality of projections thereon for successively engaging the wrapper on the side opposite the layer member during the laying operation, said lifting member and controlling device being arranged to move simultaneously in the same direction.

10. In a wrapping machine, the combination with a layer member of a controlling device to engage and support a flap on the side opposite the layer member, said controlling device having a plurality of projections thereon for successively engaging the wrapper on the side opposite the layer member during the laying operation, said layer member and controlling device being held in spaced relation throughout the operating cycle.

11. In a wrapping machine, a mold for receiving a wrapper, means for forcing a wrapper into said mold with unequal flaps of said wrapper projecting from the opposite sides of the mold, a layer member for engaging the longer flap and to fold it over the article to be wrapped, and a controlling device for supporting said flap on the side opposite the layer member, said layer member and controlling device being held in spaced relation throughout the operating cycle.

12. In a wrapping machine, a mold for receiving a wrapper, means for forcing a wrapper into said mold with unequal flaps of said wrapper projecting from the opposite sides of the mold, a layer member for engaging the longer flap and to fold it over the article to be wrapped, a controlling device for supporting said flap on the side opposite the layer member, said layer member and controlling device being held in spaced relation

75

throughout the operating cycle, and means for folding the overhanging edge of the longer flap down one side of the article to be wrapped.

13. In a wrapping machine of the class described, a flap lifter, a controlling device arranged to cooperate with the flap lifter to hold the flap between them at the beginning of the laying operation in a position in readiness for engagement of the flap by a laying member, said laying member and controlling device being arranged to move simultaneously in the same direction during the laying operation.
14. In a wrapping machine, the combination with a layer member of a controlling device to engage and support a flap on the side opposite the layer member, said controlling device having a member thereon for successively engaging the wrapper on the side opposite the layer member during the major portion of the laying operation, said layer member and controlling device being held in spaced relation throughout the operating cycle.
15. In a wrapping machine, a mold for receiving

a wrapper, means for forcing a wrapper into said mold with flaps of said wrapper projecting from the opposite sides of the mold, a layer member for engaging one of said flaps and to fold it over the article to be wrapped, and a controlling device for supporting said flap on the side opposite the layer member during the major portion of the laying operation, said layer member and controlling device being held in spaced relation throughout the operating cycle.

16. In a wrapping machine, a mold for receiving a wrapper, means for forcing a wrapper into said mold with flaps of said wrapper projecting from the opposite sides of the mold, a layer-member for engaging one of said flaps and to fold it over the article to be wrapped, a controlling device for supporting said flap on the side opposite the layer member, and for moving the second flap out of the path of the first flap whereby the second flap is prevented from becoming entrapped under the first flap.

ALFRED GERMAN ROSE.
